UNITED STATES PATENT OFFICE

WILLIAM C. MARSHALL AND JOHN H. TURNER, OF NICEVILLE, FLORIDA

DOOR OR WINDOW CASEMENT CATCH

Application filed March 30, 1931. Serial No. 526,524.

The invention relates to a door or window casement holder, and more especially to a door or window casement catch.

The primary object of the invention is the provision of a holder or catch of this character, wherein a swinging door or window casement can be latched or held caught in open position, the holder or catch being of novel form so that on the swinging of either the door or casement, the latter will not become damaged or marred by impact or otherwise.

Another object of the invention is the provision of a holder or catch of this character, which is extremely simple in construction, thoroughly reliable and efficient in its purpose, readily and easily applied to a support or removed therefrom, neat and attractive in appearance, strong and durable, and inexpensive to manufacture.

With the above and other objects in view, the invention consists in the features of construction, combination and arrangement of parts, as will be hereinafter more fully described in detail, illustrated in the accompanying drawing which discloses the preferred embodiment of the invention, and pointed out in the claim hereunto appended.

In the accompanying drawing:—

Figure 1 is a vertical sectional elevation through a door or window casement holder or catch constructed in accordance with the invention, showing by dotted lines the knob of the door or casement engaged therewith, the door being fragmentarily shown in dotted lines.

Figure 2 is an elevation of the holder or catch.

Figure 3 is a detail plan view of the buffer associated with the holder or catch.

Similar reference characters indicate corresponding parts throughout the several views in the drawing.

Referring to the drawing in detail, the catch or holder comprises preferably a face plate 5, in this instance of rectangular shape and made from metal, although the same may be of any other shape and made from any other suitable material, the plate being secured to an abutment wall or vertical up-

right in any suitable manner, to confront the knob of a door or window casement when either the door or window casement is swung to open position and in this instance, said plate is secured by screws 6, as is clearly shown in Figure 1 of the drawing. Superimposed centrally of this plate 5 is a resilient disk 7 having a raised convex buffer center 8, which is adapted to protrude through the catch or holder proper hereinafter fully described.

The catch or holder proper comprises a pair of spaced opposed resilient jaws 9, these forming the end portions of a substantially U-shaped frame 10, the medial portion of which is straight and provided with a central aperture or hole 11 for accommodating the buffer 8, said straight medial portion 10 being superimposed upon the disk 7 and is made fast to the plate 5 through the medium of fasteners 12 passed through said medial straight portion 11, the disk 7 and secured in the plate 5. The jaws 9 have outwardly flared free end portions 13 with outwardly curled extensions 14, while said jaws between the portions 13 and the medial straight portion 10 are outwardly bowed, as at 15, to constitute a seat therebetween for the knob 16 of a swinging door or window casing, a portion of the door being indicated at 17 in Figure 1 of the drawing.

In the use of the holder or catch, when the door or window casing is swung to open position, the knob 16 will be forced between the portions 13, causing the automatic spreading of the jaws 9, whereby the latter will be snapped into engagement with the knob on the contact thereof with the buffer 8 and become seated in the outwardly bowed portions 15 of said jaws, thus holding the door or window casement in open position. On swinging the door to closed position, the knob 16 will ride out from between the resilient jaws 9 of the catch or holder proper, the buffer 8 being designed to prevent damage to the knob when forced into the catch or holder proper, as will be clearly apparent.

What is claimed is:—

A door or window casement catch comprising a flat base plate having a central sub-

stantially circular-shaped seat in the outer face thereof, a resilient buffer engaged in said seat and having a convexed exposed outer face, an open resilient clip having a medial portion provided with an opening of less diameter than the seat and accommodating a major portion of the convexed outer surface of said buffer and also superimposed upon the base plate with the opening matching the seat to retain the buffer therein, means detachably securing the clip to the base plate and disposed at opposite sides of the seat therein, and outwardly flared terminals on the clip at the open side thereof and having outwardly and inwardly curled free ends.

In testimony whereof we affix our signatures.

WILLIAM C. MARSHALL.
JOHN H. TURNER.
